The dominant features of my design reside in those portions shown in full lines on the drawing.

I claim:

The ornamental design for a magnetic tape transport cabinet, substantially as shown and described.
